(57) **CLAIM**

The ornamental design for an antenna, as shown and described.

DESCRIPTION

FIG. 1 is a top plan view of a first embodiment of an antenna, showing our new design;

FIG. 2 is a front elevation view thereof;

FIG. 3 is a bottom plan view thereof;

FIG. 4 is a top perspective view thereof;

FIG. 5 is a top plan view thereof, with the unclaimed environment not shown;

FIG. 6 is a front elevation view thereof, with the unclaimed environment not shown;

FIG. 7 is a top plan view of a second embodiment of an antenna, showing our new design;

FIG. 8 is a front elevation view thereof;

FIG. 9 is a bottom plan view thereof;

FIG. 10 is a top perspective view thereof;

FIG. 11 is a top plan view thereof, with the unclaimed environment not shown;

FIG. 12 is a front elevation view thereof, with the unclaimed environment not shown;

FIG. 13 is a top plan view of a third embodiment of an antenna, showing our new design;

FIG. 14 is a front elevation view thereof;

FIG. 15 is a bottom plan view thereof;

FIG. 16 is a top perspective view thereof;

FIG. 17 is a top plan view thereof, with the unclaimed environment not shown;

FIG. 18 is a front elevation view thereof, with the unclaimed environment not shown;

FIG. 19 is a top plan view of a fourth embodiment of an antenna, showing our new design;

FIG. 20 is a front elevation view thereof;

FIG. 21 is a bottom plan view thereof;

FIG. 22 is a top perspective view thereof;

FIG. 23 is a top plan view thereof, with the unclaimed environment not shown; and,

FIG. 24 is a front elevation view thereof, with the unclaimed environment not shown.

The broken lines show unclaimed environment only and

form no part of the claimed design.
